DESIGN FOR A CLOTH COVERED CONCAVE EYELET BUTTON

William Novick, Brooklyn, N. Y.

Application November 24, 1942, Serial No. 108,866

Term of patent 14 years

To all whom it may concern:

Be it known that I, William Novick, a citizen of the United States, residing at the Borough of Brooklyn, in the county of Kings and State of New York, have invented a new, original, and ornamental Design for a Cloth Covered Concave Eyelet Button, of which the following is a specification, reference being had to the accompanying drawing forming part thereof.

Fig. 1 is a top perspective view of a cloth covered concave eyelet button, showing my new design;

Fig. 2 is a bottom view of the button; and
Fig. 3 is an enlarged section as on the lines
3—3 of Fig. 1.

My design for a cloth covered concave eyelet button of the specific configuration as shown is characterized by the cylindrical flanges at the top and the bottom outer edges thereof.

I claim:

The ornamental design for a cloth covered concave eyelet button, as shown and described.

WILLIAM NOVICK.
